UNITED STATES PATENT OFFICE.

JOHN WILLIS, OF CANTON, OHIO.

WOOD-POLISHING MACHINE.

SPECIFICATION forming part of Letters Patent No. 278,647, dated May 29, 1883.

Application filed April 6, 1883. (No model.)

To all whom it may concern:

Be it known that I, JOHN WILLIS, a citizen of the United States, residing at Canton, in the county of Stark and State of Ohio, have 5 invented certain new and useful Improvements in Wood-Polishing Machines, of which the following is a specification, reference being had therein to the accompanying drawings.

Figure 1 is a side elevation of my improved 10 apparatus. Fig. 2 is a sectional view of the casing which surrounds the polishing-head. Fig. 3 is a plan view of a portion of the air-pipe. Fig. 4 is a section of the air-pipe at one of the joints.

15 In the drawings I have represented, at A, a part of a wall or frame-work of a mill or structure utilized to provide the main support for the smoothing or polishing apparatus. Said apparatus may be of any well-known or preferred character. In the drawings I have 20 shown one having an axis, B, situated vertically, and mounted in bearings provided by brackets *bb*. The axis or shaft carries between the brackets a sleeve and pulley, C C', by which power is imparted to a belt or chain, *c*, which conveys it to the operative parts at the outer end. To this shaft or axis B the power 25 can be imparted from any suitable point. I have shown it as being rotated by means of 30 a shaft, D, having a pulley, *d*, connected with a pulley, *d'*, on the shaft or axis B by a chain or belt, D'.

E represents the main part of the swinging frame or support, it having two hinged connections at *e e'* with the shaft or axis B. It 35 extends outwardly from said shaft to any suitable length, preferably narrowing toward the outer end. In the outer end is a vertical shaft, F, receiving power from the chain or belt *c*, and imparting said power to another shaft, G, 40 in the supplemental outer swinging frame, H, pivotally connected with the part E on the line of the axis or shaft F. The shaft G carries at the lower end a revolving head, I, which 45 may be utilized to carry either a metallic cutter or polishing implement, or which may be adapted to have sand-paper or other smoothing and polishing material attached thereto. This head and the operative material or de- 50 vices carried thereby are inclosed in a casing,

J, which surrounds it, and which forms an inclosed chamber or space directly above the surface of the material that is being operated upon. The casing is shown as being cylindrical in general form, having an open bottom and a closed top or cover, and as being so constructed as to make the length of it adjustable. This can be done by having the vertical wall made in two or more sections united telescopically and provided with clamping devices, 55 by which the different sections can be held together at any required points. Two sections, *j j'*, are shown, the outer lower one, *j'*, being provided with slots *j² j²*, through which pass clamping set-screws *j³*, engaging with the other 60 section, *j*, and which can be used to clamp the two sections together.

There is a space or passage-way between the head I and the casing J, as shown at *i*, communicating with a chamber, *i'*, above the head I. 70 This latter chamber is connected by means of a tight conduit or pipe with the eye or other suitable part of a suction-fan at K. When the fan is in operation a strong current of air can be drawn through the tubular connection between the fan and the chamber *i'*. The air enters the chamber *i'* through the annular passage at *i*, it passing to said passage from a space of considerable area around the head. 75

I have shown a sectional tubing made in 80 three main sections, L L' L². The section L extends from the vertical portion *l*, which communicates directly with the chamber *i*, to the intermediate portion, L', with which it is connected by an axial part, *l'*, fitting into or 85 around a corresponding axial part, *l²*, on the section L'. The axis of the said parts *l* and *l²* coincide with the axis on the shaft F, so that said sections L and L' of the conduit can be rocked relatively to each other when the parts 90 E and H of the frame below are being rocked or oscillated. The intermediate section, L', is connected with the fan-section L² in a similar manner—that is to say, by means of two axial parts, *l⁴* and *l⁵*, one fitting within the other, 95 and having an axis of rotation coinciding with the axis of shaft B. When the tubular connection between the fan and the initial dust-chamber *i'* is made in this way there is a perfect flexibility at all the joints of the mechan- 100

ism, and there will be no material interference with the air-current passing between the said parts.

I do not wish to be limited to the exact form of the extensible or variable chamber J, as others can be employed more or less similar without departing from the spirit of my invention.

I am aware of the fact that heretofore in machines somewhat similar to this use has been made of tubular ducts, through which the dust was carried away, and I do not therefore broadly claim such ducts as my invention; but in the previous construction of which I have knowledge the sections of the duct were joined in such manner as to necessitate the employment of large chambers at the points of junction. These chambers are objectionable not only on account of the greater expense, but also from the fact that they provide pockets or gathering-places, in which the dust settles in large quantities, tending to choke up the passage-way. When the sections of the tubes are joined together in the manner which I have shown—that is to say, by having the end of one inserted directly into the opposing end of the other—an unbroken path is provided, without pockets

or corners for the deposit of dust, and, moreover, the machine can be made much simpler and at much less expense.

What I claim is—

1. In a machine for polishing or sandpapering, the combination of a swinging sectional frame, the smoothing tool or material carried thereby, a sectional tubular duct secured to the frame and having its sections corresponding to those of the frame, and a chamber carried by the sectional swinging frame, and constructed with an extensible wall which can be moved toward and from the material to be operated upon, substantially as set forth.

2. The combination of the frame, the polishing or smoothing tool or material carried thereby, the duct for exhausting the dust-laden air, and the casing which surrounds the tool or polishing material, having the extensible section j', substantially as set forth.

In testimony whereof I affix my signature in presence of two witnesses.

JOHN WILLIS.
